X-RAY TUBE TRUNNION OR SIMILAR ARTICLE

Eugene P. Thomas, Baltimore, Md., assignor to Westinghouse Electric Corporation, a corporation of Pennsylvania

Filed May 11, 1966, Ser. No. 2,248

Term of patent 14 years

(Cl. D83—1)

FIG.1.

FIG.2.

FIG.3.

FIG.4.

FIG.5.

FIG.6.

FIGURE 1 is a top plan view of an X-ray tube trunnion or similar article, showing my new design;

FIG. 2 is a front elevation thereof;

FIG. 3 is a side elevation thereof;

FIG. 4 is a bottom plan view thereof;

FIG. 5 is a rear elevation thereof; and

FIG. 6 is a front perspective thereof.

The broken lines illustrating the X-ray tube housing are shown for purposes of illustration only.

The dominant features of my design reside in the portions shown in full lines.

I claim:

The ornamental design for an X-ray tube trunnion or similar article, substantially as shown and described.
